SAFETY HITCH FOR TRACTORS

Seth Sidwell Ellis, Waynesville, Ohio

Application July 31, 1943, Serial No. 496,911

2 Claims. (Cl. 280—33.44)

This invention appertains to new and useful improvements in an attachment for Ford tractors which acquire the use of power from the usual hydraulic mechanism and is especially associated with the Ferguson type of draft mechanism.

The principal object of the present invention is to provide a hitch assembly of the character which will enable the operator to safely and conveniently adjust the draw-bar or implement hitch to any desired position without stopping or leaving the seat of the tractor.

Another important object of the invention is to provide an attachment of the character stated which permits of either a rigid or swinging draw-bar by the provision of special brace members.

Another important object of the invention is to provide an attachment of the character stated which permits the draft assembly to act automatically as a plowing guide by establishing the tractor and plows as a rigid unit which holds the furrow wheel of the tractor against the furrow wall, thus relieving the operator from constantly steering the tractor.

Other objects and advantages of the invention will become apparent to the reader of the following description.

In the drawings:

Figure 1 represents a vertical longitudinal fragmentary sectional view and showing the draft assembly.

Figure 2 is a fragmentary top plan view.

Figure 3 is a longitudinal sectional view through one of the side braces showing the same in yielding position.

Figure 4 is a side elevational view of one of the side braces showing the same adjusted to a non-yieldable position.

Figure 5 is a perspective view of one of the attaching plates.

Figure 6 is a perspective view of one of the attaching members for the side braces.

Figure 7 is a fragmentary side elevational view of the slotted bar of one of the side braces.

Figure 8 is a perspective view of the drawbar connector plates.

Figure 9 is a rear elevational view of the drawbar supporting keeper.

Figure 10 is a side elevational view of the drawbar supporting keeper.

Referring to the drawings wherein like numerals designate like parts, it can be seen in Figure 1 that numeral 5 denotes the rear axle of a tractor while numeral 6 denotes a housing therefor.

Conventional hydraulic lift mechanism for this type of Ford tractor employs hydraulically actu-

ated arms 7, 7 which are connected by universal coupling 8 to adjustable connectors 9, which in turn, are pivotally secured as at 10 to pivotal drawbar carrying arms 11.

Numeral 12 denotes a conventional drawbar having pintles 13 at its ends for disposition through the outer ends of the arms 11 and also through the openings in the rear ends of angular bar members 14, it being seen in Figure 8 that these angular members 14 have openings 15 and 16 at the ends thereof.

Chain sections 17, 17 extend from said members 14 to a ring 18 and from the ring 18 a chain 19 extends and is adapted to be adjustably disposed through a keeper element generally referred to by numeral 20 and which is clearly shown in Figures 9 and 10. This keeper element consists of an elongated plate 21 having a bearing barrel 22 at its midpoint, while its upper end 20 is provided with a keyhole-shaped opening 23, and to the narrow portion of which a link can be set for abutment in order that the chain arrangement 17, 19 will be held and the drawbar 12 properly supported. As is clearly shown in Figures 1 and 10, a suitable brace 24 is provided for this keeper 20.

Numeral 25 denotes the usual top link pin of this type of tractor, and numeral 26 denotes a rocker which is swingably mounted in conjunction therewith, and which, in turn, supports the keeper 20.

The barrel 22 of the keeper element 20 is pivoted, as at 22', to the rocker 26 with the opening 23 uppermost and the lower end of the keeper element adapted to bear against the differential housing 6' of the tractor. The rocker 26 forms part of the usual overload control mechanism of the tractor which need not be described, since it is well known in the art. By inserting selected links of the chain 19 in the opening 23, the height of the draw bar 12 may be varied as required.

Thus it can be seen, that the operator, sitting on the tractor seat A need not leave his seat in order to adjust the drawbar support 17, 19. By merely turning in his seat and reaching backwards, he may grasp the forward end of the chain 19, lift a link out of the narrow portion of the opening 23, pull the said chain through the wider portion of said opening to lift the draw bar support 17, thus lifting the draw bar 12, and then lower another link of the chain 19 into the narrow portion of the opening 23.

This improved assembly is provided with side brace units 27 which may be set for sliding action or set rigidly.

Each of these units 27 consists of an elongated bar 28 having one end threadedly disposed into an internally threaded coupling sleeve 29. A threaded eye 30 is also disposed into the sleeve 29 and through this eye 30 is disposed a securing bolt. The other end of the bar 28 is slotted as at 31 for receiving a cross pin 32 disposed through a tube section 33 which is aligned with a tube section 34 also located on the bar 28 and which is held to the bar 28 by a cotter key or the like 35. The opposed ends of the tube sections 33, 34 are provided with interlocking protuberances 36, 37, respectively. These protuberances correspond in length substantially to the length of the slot 31, and when the protuberances 36, 37 are interlapped as in Figure 3, the pin 32 is in the inner end of the slot 31 and the brace unit 27 is contracted but conditioned for extension since the bar 28, sleeve 29 and eye 30 may slide outwardly of the tube section 33 and the slot 31 may move relative to the pin 32. This permits the draw bar 12 to swing laterally of the tractor. However, when the cotter pin 35 is removed the tube section 34 may be given a half turn, and moved away from the tube section 33, whereby the tubes 33, 34 will be in the relative positions shown in Figure 4 with the pin 32 in the outer end of the slot 31, with the result that the unit 27 is extended and there can be no longitudinal relative movement, said pin 35 being replaced, between the tube sections 33, 34 and thus the draw bar will be held rigid against swinging laterally of the tractor.

The eyes 30 of the brace units 27 are adapted to be interposed between apertured upper and lower plates 37 which also embrace the rear ends of the drawbar arms 11 and are provided with selective apertures 37' for bolting said eyes 30 thereto when the units 27 are contracted or expanded. The upper and lower plates 37 being bolted together by bolts or other means 38.

The outer ends of the tube sections 33 are equipped with clamp heads 39 which engage over bolts 40 and which are disposed through openings 41 in the side walls 42 of angular brackets 43, these brackets being suitably secured to the rear axle housing 6 shown in Figures 1 and 2.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a tractor hitch, a drawbar and a flexible support for said drawbar, hydraulically operative arms for the drawbar and brace units for said arms, said brace units each consisting of a brace member constructed and arranged to permit extensibility or rigidity, each of said brace members consisting of a pair of tubular sections, one of which is swingably connected to the tractor, a bar disposed through one of the sections and into the other section and formed with a slot at its inner end, a removable detent element disposed through the tractor attached tubular section and through the slot in the bar, the other end of the bar being in secured relation to the drawbar, said tubular sections at their opposed ends being provided with interlappable protuberances which, when in opposed relation, rigidify and prevent extensibility of the brace member and which, when in interlapped relation, provide a sliding connection between the bar and the tractor attached tubular section.

2. In a tractor hitch, a draw bar, a flexible support for said bar, hydraulically operative carrying arms for the draw bar, and a brace unit for one of said arms comprising a bar pivoted at one end to said arm, a tubular section pivoted at one end to said tractor and in which said last-mentioned bar is slideable endwise, means connecting said last-mentioned bar to said section for limited endwise sliding movement therein, a second tubular section on said last-mentioned bar rotatable and endwise movable thereon in end-to-end relation to the first-mentioned tube section and adapted to be secured to said last-mentioned bar to prevent endwise sliding of the same, and means to secure said second-mentioned section to said last-mentioned bar.

SETH SIDWELL ELLIS.
